UNITED STATES PATENT OFFICE.

HAROLD A. DODGE, OF ESSEX FELLS, AND WALTER J. LEATHERROW, OF NEWARK, NEW JERSEY, ASSIGNEES TO HOWE BAUMANN BALLOON CO., OF NEWARK, NEW JERSEY, A CORPORATION OF NEW JERSEY.

MEANS FOR INFLATING BALLOONS AND THE LIKE.

1,329,512.

Specification of Letters Patent.

Patented Feb. 3, 1920.

Application filed October 9, 1915. Serial No. 54,967.

To all whom it may concern:

Be it known that we, HAROLD A. DODGE and WALTER J. LEATHERROW, the said DODGE being a citizen of the United States, and residing at Essex Fells, Essex county, and State of New Jersey, and the said LEATHERROW also being a citizen of the United States, and a resident of Newark, Essex county, and State of New Jersey, have invented a certain new and useful Means for Inflating Balloons and the like, of which the following is a specification.

This invention is a device whereby inflatable articles, such as toy balloons of all kinds, may be readily blown up and the inflating medium retained within said article, the object being to provide a simple and effective device which can be manufactured economically.

The invention embodies a mouth-piece serving as a valve-casing, a valve positioned with said mouth-piece, and retaining means for precluding detachment of the valve from said mouth-piece. In a preferred form, the mouth-piece is provided with a flange, the latter having a groove externally and internally thereof. Within the casing formed by the mouth-piece is positioned a loose valve composed of a single piece of thin flexible material such as rubber, said valve being free from direct attachment to the mouth-piece. The retaining means may be of various forms, but it is preferably of spring wire separate from the mouth-piece and it is sprung into position so as to lie across the open inner side of the casing or mouth-piece and in the path of the loose valve, whereby the spring retainer precludes the valve from being blown into the balloon or other article during the operation of inflating the same.

It is to be understood that when the mouth-piece is placed to the lips and air is blown through the same into the article, the loose valve is unseated from across the inflating hole, but the retainer confines or holds the valve within the mouth-piece so that it is not blown by the inflowing air into the balloon. The valve is pressed or forced to its seat by the pressure of the air within the article, said valve being composed of flat, thin, flexible material so as to expose a

relatively large area to the pressure of the air and to result in the valve being pressed tightly against the mouth-piece at all points around the inflating aperture. Preferably the metal around the aperture is punched so as to form a bead internally of the mouth-piece, against which bead the flexible valve is pressed in order to prevent the air from escaping.

It may be stated that the device consists of few parts easily made and quickly assembled so as to attain the desired economy of manufacture, but at the same time the valve is easily operated and it is efficient in performing the important function of retaining the air for an indefinite time so as to keep the article in an inflated condition.

In the drawings,

Figure 1 is a view of a balloon equipped with an inflating valve of this invention.

Fig. 2 is a section on an enlarged scale through the valve with the neck of the balloon applied thereto.

Fig. 3 is an inside view of the mouth-piece, the retainer and the valve.

The mouth-piece A is provided with a central inflating aperture a and with a rim or flange b, the latter extending at right angles to the plane of the plate forming the mouth-piece. Around the mouth-piece on the interior thereof is a bead c concentric with the axis of the inflating aperture a and so as to form a bead internally of the mouth-piece simultaneously with the operation of punching the aperture therein. The rim or flange b is provided with an exterior groove b', the edge of the rim or flange being turned inwardly so as to form an interior groove b'', the entire mouth-piece being pressed or struck up from a single piece of metal at one or more operations.

Positioned within the chamber formed by the mouth-piece is a valve C, the same unattached to the mouth-piece and consisting of a single piece of thin flexible material such as rubber.

The valve C is prevented from blowing out of the mouth-piece when the article is inflated by the operation of a retainer B, the same co-operating with the mouth-piece and being positioned in the path of the

loose valve C. Preferably, said retainer is 5 separate from the mouth-piece and it is composed of spring material so that it may be snapped into position within the mouth-piece for the purpose of holding itself by frictional contact with said mouth-piece. This retainer B may be composed of different materials and be embodied in many different forms, but it is preferred to produce 10 the retainer from a piece of spring wire which is bent into a form to serve as a barrier for the loose valve and at the same time expose the valve to the pressure of the inflating medium. As shown, the retainer is 15 bent from a single piece of wire to bring its members into crossing relation and to present a number of points adapted for frictional engagement with the wall of the interior groove b^2 , whereby the retainer may be 20 rapidly and economically made from wire and easily and quickly assembled with respect to the mouth-piece by snapping said retainer into the groove b^2 .

From the foregoing description it is apparent 25 that the mouth-piece may be struck up from sheet metal, the valve cut from a piece of rubber or other material, and the retainer, bent from a piece of wire, after which the valve may be positioned within the mouth-piece and the retainer snapped 30 into frictional engagement with said grooved mouth-piece, thus completing the valved mouth-piece ready for application to, or for use in conjunction with, the article 35 to be inflated.

As hereinbefore stated, the article may be any inflatable device composed of rubber or other material, such as a toy balloon, indicated at D. As is usual in the art, the balloon 40 is provided with a flexible neck integral with the rubber material of the balloon. To apply the valved mouth-piece to the balloon or other article it is only necessary to expand the edge portion of the neck 45 E into frictional engagement with the external groove of the mouth-piece, whereupon the inherent elasticity of the flexible neck draws or contracts so that the edge portion of the neck will have tight frictional engagement 50 with the externally grooved flange of the mouth-piece.

When it is desired to inflate the article the mouth-piece is placed to the lips and air is blown through the aperture a into the balloon, the inflowing air displacing the loose valve from the perforated plate of the mouth-piece. At this time the retainer B precludes the unattached valve from passing 55 with the inflowing air into the article to be inflated, but when the operator wishes to blow any air through the mouth-piece, the pressure of the air within the article acts upon the loose valve in a manner to force the same into tight frictional contact with the mouth-piece and over the aperture 60 65

therein, the flexible character of the valve permitting it to conform to the bead or groove of the mouthpiece and thereby close the article against the escape of air through the aperture in the mouth-piece. 70

Having thus fully described the invention, what we claim as new, and desire to secure by Letters Patent is:

1. A device for use on inflatable articles embodying a mouth-piece, a valve positioned within the mouth-piece and adapted to be held by pressure of the inflating medium into close contact with said mouth-piece, and a retainer coöperating with the mouth-piece and positioned in the path of the valve for holding the latter within said mouth-piece, said valve being unattached to the mouthpiece and being free to move in the space intermediate the retainer and the mouthpiece, whereby the valve is precluded from passing with the inflating medium into the article to be inflated. 80

2. A device for use on inflatable articles embodying a mouthpiece, a valve positioned within said mouthpiece, said valve being free from direct attachment to said mouth-piece, and a retainer separate from the mouthpiece and coöperating therewith for limiting the movement of said valve, said retainer being attachable to the mouthpiece. 90

3. A device for use on inflatable articles embodying a mouth-piece, a valve positioned within the mouth-piece and adapted to be held by pressure of the inflating medium into close contact with said mouth-piece, said valve being free from direct attachment to the mouth-piece, and a retainer separate from the mouth-piece and engaging frictionally therewith so as to be in the path of the loose valve for precluding the latter from passing with the inflowing inflating medium into the article to be inflated. 100

4. A balloon or like inflatable article, provided with an elastic neck, a mouthpiece having a flange, said flange being provided exteriorly thereof with a groove into which is fitted the edge portion of said neck so as to retain the mouthpiece in position by the frictional contact of the neck with said mouthpiece, a valve positioned interiorly of said mouthpiece, and means for retaining the valve within said mouthpiece. 110

5. A device for use on inflatable articles embodying a mouth-piece, a valve composed of a thin flexible material and positioned loosely within the mouth-piece so as to be pressed by the inflating medium into tight contact with said mouth-piece, and a spring retainer having frictional contact with the mouth-piece and positioned in the path of said loose valve. 120

6. A device for use on inflatable articles embodying a mouth-piece provided with an internal groove, a retainer sprung into the mouth-piece and frictionally held in the 130

groove thereon, and a flexible valve confined loosely in position between the retainer and a wall of the mouth-piece.

7. A device for use on inflatable articles embodying a mouth-piece provided around the inflating aperture with a bead positioned interiorly of said mouthpiece, a valve composed of thin flexible material and free from direct attachment to the mouth-piece, said 10 valve being pressed by the inflating medium against the mouth-piece and against the bead thereof, and means for retaining the loose valve within the mouth-piece.

8. A balloon, or like inflatable article,

provided with an elastic neck, a mouthpiece 15 insertible into the neck and retained in position relatively thereto by frictional engagement between the neck and the mouthpiece, a valve composed of thin flexible material positioned within said mouthpiece, said 20 valve being free from direct attachment to the mouthpiece, and means for retaining the valve in operative position within said mouthpiece.

In testimony whereof we have hereunto 25 subscribed our names.

HAROLD A. DODGE.

WALTER J. LEATHEROW.
